GARMENT HANGER

Samuel I. Cohen, Newton, Mass.

Application November 26, 1943, Serial No. 511,825

4 Claims. (Cl. 223—91)

1

This invention relates to the art of garment supporting devices. More particularly it pertains to hangers adapted to provide a positive gripping function. In its preferred embodiments, the invention is directed to garment hangers which are especially effective for supporting skirts, trousers and the like in vertical position in order to minimize any tendency to wrinkling or form distortion.

Hanger devices in substantially universal usage at the present time for vertically suspending skirts, trousers and similar apparel are in considerable measure dependent upon metal stock, principally wire, for fabrication, especially since their intrinsic structural design has relied upon the inherent resiliency characteristics of metal for attaining the desired function.

While these hangers have afforded generally satisfactory service, they have been largely devoid of esthetic significance, and the types preponderantly used have not been free from functional objections. For example, the simpler hanger structures, which are by far in greatest demand, have been limited in their gripping function to two restricted points or comparatively narrow zones, and have not afforded any means for variation of these gripping points commensurate with the dimension of the garment, such as the cuffs of the trousers or the waist band of a skirt. Attempts to obviate this limitation have resulted in unduly involved structures as opposed to the desired simplicity and attendant sturdiness.

Moreover the dependency of the clamping type of hanger upon metal stock for manufacture has per se been a source of substantial difficulty, since it is well recognized that circumstances frequently prevail which result in a scarcity of metal supplies, and this has accentuated the desirability of an effective supporting device that is free from metal requirements in its details of construction. Despite the desirability for non-metal clamping hangers, the difficulties embodied in their manufacture have resulted in few, if any, efficient devices of this type.

It is an object of this invention to obviate such difficulties and uncertainties as hereinabove indicated.

Another object is to provide a device for supporting garments which will manifest a gripping or clamping function commensurate with the dimension of the garment at the zone of support.

An additional object of the invention is to attain a garment hanger particularly effective for suspending skirts, trousers, et cetera by uniform

2

gripping function, variable in accordance with the dimension of the garment along the line or zone of support, exemplified by a skirt waist band or trouser cuffs.

5 An important object is to produce a clamping type skirt or trousers hanger which is free from metal in its fabrication.

A further object is to obtain a non-metal skirt or trousers hanger which affords a substantial zone of gripping function, the zone being susceptible to variation commensurate with the dimension of the garment at the zone of support.

An added object is to devise a non-metal garment supporting device which is comparatively esthetic in its appearance, sturdy, compact, although essentially simple in its details of structure or operation, and provides an effective, positive gripping function on the garment.

Other objects, advantages, and features of the 20 invention will become apparent from the following description read in connection with the accompanying drawing in which similar elements are designated by like numerals:

Fig. 1 is a side elevation of garment hanger 25 constructed in accordance with the present invention, and shown gripping the waist band of a skirt, indicated in fragmentary portion;

Fig. 2 relates to a cross sectional view taken along the line 2—2 of Fig. 1;

30 Fig. 3 presents a bottom plan view of the garment hanger shown in Fig. 1, revealing the coordination of the clamping members;

Fig. 4 provides a fragmentary elevation of a 35 desirable end structure for the clamping members;

Fig. 5 represents a cross section viewed along line 5—5 of Fig. 3, embodying one modification of the end structure for the clamping means;

Fig. 6 indicates a cross sectional detail of a 40 locking or clamping button taken on the line 6—6 of Fig. 1;

Fig. 7 sets forth in fragmentary side elevation, a modified hanger structure with seats provided in the slot for locking engagement with the 45 clamping button;

Fig. 8 comprises a cross sectional view of a modified clamping button structure;

Fig. 9 pertains to a modified bottom plan view of an end of the hanger device, similar to that shown in Fig. 3, but omitting the wedge segments from the clamping members.

Referring more particularly to the features of 50 invention embodied in the modifications shown by the various figures of the drawing, the hanger device of Fig. 1, generally designated as 10, is

illustrative of a desirable embodiment of the invention. It comprises a body portion 11, 11', desirably arcuate in form, provided with slots 12, 12' which follow the contour of the body portion and are preferably positioned approximately midway between the edges 13, 13' of the body portion. As shown, two slots 12, 12' are provided, one on each of the respective sides of body portion 11, 11', with the suspension hook portion of the hanger positioned between the slots. There is however no intent to be restricted to these details of construction, since they are intended to be primarily by way of exemplification and not restriction.

Thus slots 12, 12' may in fact be combined to a single slot by omitting the structural material between them shown in Fig. 1. On the other hand, alternative details of design may result in more than the two slots 12, 12' shown.

The function of slots 12, 12' is in effect that of guide means for clamping buttons 14, 14' which facilitate the gripping action of clamping members 21, 22 on garment 17, as will be further apparent from the additional consideration hereinbelow. An effective length for slots 12, 12' may be approximately defined as that extending between either designating line 19 or 19' and end portions 18, 18' respectively of the hanger. It will be noted that the hanger body area 16 between designating lines 19, 19' broadly determines the base portion of the suspending hook 20, and that the end portions 18, 18' embrace portions of the hanger spaced from the somewhat downwardly directed extremities 15, 15'. However, as previously suggested, the length of the slots is subject to variation pursuant to predetermined design or contemplation.

The suspension hook 20 is appropriately positioned relative to the center of gravity of the garment hanger as a whole in a manner to maintain a state of balanced equilibrium especially when the hanger is carrying its garment load.

In accordance with a desirable embodiment of hanger construction, it may be manufactured from two complete, integral sections A, B which are appropriately laminated together, as will be apparent from Figs. 2 and 3. Thus these sections should be symmetrical in every detail in order to permit precise overlapping of all of their respective parts including suspending hook 20 and the arcuate body portions 11, 11' embracing slots 12, 12', clamping members 21, 22, end portions 18, 18' and edges 13, 13'. The actual zone of attachment of A to B, designated as 23, desirably embraces the complete suspending hook portions 20, including the area 16 which coincides with the body portion of the hanger between designating lines 19, 19'.

The manner of attachment between sections A and B may be through appropriate adhesive composition or by resort to any mechanical expedient, including a nailing together of the specified parts or by interlocking or interfitting them. Accordingly the body portions of A and B extending from either designating line 19 or 19' to the extremities 15, 15' respectively are essentially unattached, and determine the clamping members 21, 22 between which the garment is sustained. Differently stated, while the area between designating lines 19, 19', embracing body portion 16 and the complete suspending hook 20, are securely attached to each other in any predetermined manner, the gripping portion of the hanger embracing clamping members 21, 22, including the arcuate portions determining slots

12, 12' are not permanently affixed to each other, although they are substantially contiguously positioned. By this structure the clamping members 21, 22 manifest a spring-like coaction relative to each other, with the supported article, such as the skirt, gripped in the space between them.

In the structural modification embraced by Figs. 3-5, the end portions 18, 18' of clamping members 21, 22 may be provided with a wedge segment 24 which is attached by an adhesive or in any desired manner. The function of this wedge means, if utilized, is primarily to accentuate the clamping action in this area. However an effective gripping function is attainable without resort to any auxiliary expedients such as wedge segments 24, since the thickness of the garment being supported is sufficient to utilize the inherent spring coaction between the clamping members for effective gripping function. In Fig. 9, there is shown a bottom plan view of a hanger structure which has proven quite satisfactory without the inclusion of any wedge means such as that shown in Fig. 3.

A desirable expedient for attaining efficient gripping action on the garment, quite irrespective of the details of structure at the end portions 18, 18' of clamping members 21, 22, is the provision of surface grooves 25, as indicated in Fig. 4. It will be seen that as the garment is clamped between members 21, 22 provided with grooves 25, incremental portions of the garment will be at least superficially wedged in these grooves, with the result that an enhanced gripping action is attained.

The extent of grooves 25, both with respect to their inherent dimensions and to the proportion of clamping member surface which they embrace, is subject to variation within the dictates of predetermined design and discretion. Similar to the showing of Fig. 4, it is within the contemplation of the disclosure to provide clamping members 35, 36 of Fig. 9 with gripping grooves of expedient extent and dimension, if so desired.

A desirable modification of locking means is presented in Fig. 6 wherein the clamping button is provided with an integral pin of varied dimension comprising cylindrical ends 26 and an enlarged intermediate section 27, which may be of substantially ovate form, thereby minimizing the tendency of the pin to rotate in slots 12, 12'. There is no intent however to be limited to any specific form of pin design, and an equivalent inhibitory effect upon rotation may be attained through resort to a substantially rectangular pin section in lieu of the ovate form of section 27. The heads or caps of clamping buttons 14 may be affixed to the cylindrical ends 26 of the pin in any expedient manner, such as by utilizing an adhesive or by mechanical means, exemplified by wedging the head on the pin, or by resort to nails or screws. In assembling the clamping button in its slot 12, 12' the pin will desirably be positioned in the slot prior to affixing at least one of the caps to the cylindrical end thereof.

The clamping button 28, shown in Figs. 7 and 8, represents a simplified form of locking means, the pin 29 being of uniform cylindrical shape. The manner in which the head or cap of clamping button 28 may be seated on pin 29, as well as the details of assembly relative to the guide slot 34, of the hanger body 33, within which the clamping button is seated or positioned for sliding movement to facilitate the gripping function of clamping members 31, 32, may be attained in any ex-

pedient manner such as that suggested hereinabove in the consideration of the clamping member of Fig. 6.

Fig. 7 comprises a modification of the hanger structure presented in Fig. 1, to the extent that positive locking features between the clamping member and its guide slot are contemplated. Thus the fragmentary body portion 33 embraces guide slot 34, the lower edge of which is supplied with a plurality of notches 30 within which the locking button 28 may be positioned at predetermined intervals. The form in which notches 30 occur may be subject to variation, it being merely desirable that they correspond with the shape of the clamping button pin in order to result in a seated engagement. By way of illustration, the notches 30 of Fig. 7 are expediently semi-spherical in order to appropriately accommodate cylindrical pins 29 of clamping buttons 28.

As previously described, Fig. 9 is drawn to a fragmentary elevation of a simplified clamping member structure which has performed quite satisfactorily. Clamping members 35, 36 provide uniform internal gripping surfaces 37, 38 that are free from wedge segments or analogous elements, such as indicated in Figs. 3 and 5. Desirably surfaces 37, 38 may have grooves similar to those presented on Fig. 4, to thereby facilitate the gripping function of the clamping members under the influence of clamping buttons 39.

While the construction of an optimum embodiment of garment hanger from symmetrical, laminated sections is quite expedient, there is no intent to be limited to this manner of article production. Suggestive of an alternative manufacture, the garment hanger may be attained by appropriately cutting a unitary piece of stock material having sufficient dimensions in accordance with the predetermined pattern, to satisfy the body portion of the hanger and the guide slot. The supporting hook may likewise be cut from the same piece of unitary stock, if it is sufficient to provide this member as a part of the integral structure; on the other hand, the hook portion of the hanger may comprise a separate member, fabricated from the same or different stock relative to the body portion, and is attached to the said body portion in any feasible manner. The hook member may be of metal, wood, synthetic resin or plastic composition, or other material and designed for attachment to the hanger body, as by resort to screw threads or other means.

In any event, the body portion obtained from a single piece of material is slit either completely or partially, along a line substantially bisecting the width of the hanger body, designated as C in Figs. 3 and 9. The depth to which the slit extends may desirably be through the complete thickness D of the body portion, although an operative device may be obtainable by slitting the body portion less than its thickness, but sufficient to provide the requisite clamping members. As for the longitudinal extent of the slit along the hanger body, it may desirably embrace the length between the hanger body extremities, such as 15, 15' and the designating lines 19, 19' as shown by Fig. 3. This termination of the longitudinal extent of the slit is particularly desirable in the modification where the slit projects through the entire thickness D of the hanger body.

Where the stock utilized is susceptible of molding, as in the case of synthetic resins or plastic compositions, the structural features of the invention may be substantially directly attained by molding the material as a unitary structure.

The arcuate form of body portion with the

downwardly directed ends, as in the case of Fig. 1, has functioned satisfactorily. Nevertheless the shape of the hanger is subject to variation within the scope of the invention. Thus the arcuate form of Fig. 1 may be retained, although omitting the aforementioned downwardly directed end portions; under some conditions, this modification would afford an enlarged zone of gripping contact between the clamping members and the garment. By way of further illustrative modification, the body portion may extend entirely in a horizontal plane, thereby differentiating from the arcuate type of Fig. 1.

Concerning the material stock from which the hanger may be made, this is not to be treated as of critical significance, although certain materials result in a more effectively functioning device than others. The features of construction embraced by the invention lend themselves particularly to the manufacture of garment hangers from non-metal materials, including wood, cardboard, and plastics, especially of the synthetic resin type, but this is not to be taken as precluding the construction of desirable hangers by utilizing metal stock. An optimum embodiment has been considered to be the wooden hanger of laminated construction in accordance with the description hereinabove in view of its facility of manufacture and effectiveness of performance.

A quite effectual device is also obtainable by laminating together, as described hereinabove, symmetrical hanger sections molded from synthetic resin to provide an integral structure. Any desirable manner may be resorted to for attaching the sections to each other in the appropriate areas; where the resins manifest any thermoplastic characteristics, heating may be utilized to attain the requisite attachment. As previously indicated, a one piece or unitary structure of resin or plastic composition fabrication embodying the skirt hanger features shown is within the contemplation of the disclosure; this may be made by cutting a unitary piece of stock material or by a molding procedure.

In connection with the operation of the hanger device, it will be noted that in accordance with the preferred structural embodiment as shown by Figs. 1-3, the clamping members 21, 22, manifest a spring-like function relative to each other between the extremities of the hanger and the designating lines 19, 19', the zone 16 involving the permanent attachment of the laminations to each other, functioning as the pivotal area for the said spring-like characteristics of the clamping members. As shown in Figs. 3 and 9, there is a slight tendency for the clamping members to be somewhat spaced apart in the direction proceeding from designating lines 19, 19' respectively, to the hanger extremities 15, 15', thereby facilitating the introduction between the clamping members of the garment to be clasped.

With the clamping buttons in a position proximate the respective designating lines 19, 19' and desirably at the end of the guide slots 12, 12' the trouser cuffs or waist band of the skirt may be inserted between clamping members 21, 22, and the buttons 14 are then slid in their guide passages 12, 12' toward the extremities 15, 15' respectively of the hanger. This movement of the clamping buttons 14 serves to lock the garment between the clamping members, the garment being wedged in the internal grooved surfaces of the clamping members to attain maximum gripping function.

In the modification of Fig. 7, the clamping buttons 28 assume a locking engagement with the appropriate notch 34 into which they are forced to seat for coordinating the gripping action of clamping members 31, 32; otherwise this modification functions in essentially the same manner as the hanger of Figs. 1-3. Similarly the modification of Fig. 9 functions in a manner analogous to the device of Figs. 1-3.

In view of the potential gripping zone extending substantially from the respective designating lines 19, 19' to the hanger extremities, it will be seen that the garment hanger of the invention lends itself to the support of the garments of varying dimension, while at the same time affording a substantial area of actual clamping contact. Differently stated, the gripping zone is susceptible to variation commensurate with the dimension of the garment at the zone of support.

While the various figures of the drawing are directed to features of skirt hanger structure comprising optimum adaptations of the invention, it will be understood that these showings are primarily illustrative in scope and are not to be taken by way of restriction or limitation.

Pursuant to the invention, a novel, compact, esthetic garment hanger is attained which is simple but sturdy in details of construction and effective in its performance. Although these devices are particularly adapted for use as skirt or trousers supporting means, they are applicable to sustaining of other types of articles.

While I have described my invention in accordance with desirable embodiments, it is obvious that many changes and modifications may be made in the details of construction and in the combination and arrangement of parts without departing from the spirit of the invention as defined in the following claims.

Having thus set forth my invention, I claim:

1. A garment hanger comprising a body portion determining a pair of complementary clamping members, a supporting hook extending upwardly from said body portion, and means for providing a gripping function between said clamping members, said latter means being movable along a guide slot extending lengthwise within said body portion.
2. A garment hanger comprising complementary clamping members integrally attached to each other at portions intermediate their ends, a supporting hook extending upwardly from said integrally attached portions and means adapted for movement and positioning lengthwise of said clamping members for forcing said clamping members into a clamping association.
3. A garment hanger comprising complementary clamping members integrally attached to each other at portions intermediate their ends, a supporting hook extending upwardly from said integrally attached portions, guide slots intermediate the edges and extending longitudinally of said clamping members, and means for forcing said clamping members into a clamping association, said latter means being movable along said guide slots.
4. A garment hanger comprising complementary clamping members integrally attached to each other at portions intermediate their ends, a supporting hook extending upwardly from said integrally attached intermediate portions, guide slots extending lengthwise of said clamping members between said integral intermediate attached portions and the end portions of said complementary clamping members, and means movable in said slots for coordinating said clamping members to provide a clamping function.

SAMUEL I. COHEN.
